G. MERLE, SR.

CONDENSER

Filed Feb. 17, 1926

UNITED STATES PATENT OFFICE.

GEORGE MERLE, SR., OF BROOKLYN, NEW YORK.

CONDENSER.

Application filed February 17, 1926. Serial No. 88,777.

This invention relates to condensers and particularly to variable condensers, such as are commonly employed in radio apparatus; and the object of the invention is to provide a variable condenser which in addition to the usual variable features is constructed to provide for a variation in the capacity of the condenser to give the condenser a broader usage and to effect more accurate and positive tuning; a further object being to provide a condenser of the class specified composed of a plurality of movable condenser units, each unit consisting of a plurality of movable plates, which as a unit may be moved or adjusted relatively to the movable plates of another unit or units whereby the capacity of one condenser unit may be increased and decreased by adjustment relatively to one or more other units, and may be varied in either of or all of said units; a further object being to provide means whereby one or more of the movable condenser units may be adjusted relatively to the other unit and moved into inoperative position with reference to the single knob, control and operating means employed for all of the units; a still further object being to provide, in conjunction with said movable condenser units, stationary or stator plate units in connection with which the separate movable or rotary plate units cooperate; and with these and other objects in view, the invention consists in a condenser of the class and for the purpose specified, which is simple in construction and operation, efficient in use, and which is constructed as hereinafter described and claimed.

The invention is fully disclosed in the following specification, of which the accompanying drawing forms a part, in which the separate parts of my improvement are designated by suitable reference characters in each of the views, and in which:

Fig. 1 is a face view of a part of a panel showing my improved condenser mounted in connection therewith, with parts of the construction broken away and in section.

Fig. 2 is a partial section on the line 2--2 of Fig. 1.

Fig. 3 is a diagrammatic view showing an adjusted arrangement of the plates of the separate movable condenser units employed; and,

Fig. 4 is a face view of a modified form

of condenser with parts of the construction shown in section.

In practice, I employ two substantially rectangular frame members 5 and 6 within and between which are mounted four sets of movable condensers 7, 8, 9 and 10, each unit consisting of a plurality of rotor plates mounted in spaced relation on shafts 11, 12, 13 and 14 which extend through the frame members 5 and 6 centrally of the side walls thereof. The front ends of said shafts extend beyond the front frame 5 and are adapted to pass through the panel 15 of a radio apparatus. Mounted on the free ends of said shafts are operating knobs 16 having bayonet apertures 17 to receive pins 18 on the shafts 11 to 14 inclusive whereby gears 19 on the sleeve portions of the knobs 16 may be moved into and out of engagement with a drive gear 20 on a central shaft 21, mounted in the frame 5 to extend through the panel 15, and provided at its outer end with a knob dial 22 by which the shaft 21 and gear 20 may be rotated. Springs 23 are mounted within the knobs 16 and around the shafts 11 to 14 inclusive to normally hold the knobs 16 in the position shown in Fig. 2 of the drawing. By pulling the knobs 16 outwardly against the tension of said springs and moving the pins 18 into the circumferential part of the bayonet apertures 17, the gears 19 may be held out of operative engagement with the gear 20. The movable condenser unit controlled by such knob and gear may be independently adjusted when in this position.

When all of the gears 19 are in mesh with the gear 20 and the rotor plates of the separate condenser units 7, 8, 9 and 10 are in the position shown in Fig. 1 of the drawing, the straight sides of said plates will form a substantially square body of all of said condenser units with elliptical portions at each side of each plate, engaging corresponding portions at one side of two other plates. For example, the plates of the condenser unit 8 elliptically engage corresponding portions of the plates of adjacent units 7 and 9, it being understood that the plates of the opposite units 7 and 9—8 and 10 are in common alignment as clearly seen in Fig. 2 of the drawing, while the plates of the oppositely arranged units 7 and 9 are intermediate and positioned centrally of and between the

plates of the condensers 8 and 10. By rotating the knob dial 22 in one direction, all of the condenser units will be rotated and the plates of such units will gradually move outwardly to a position at ninety degrees to that shown in Fig. 1 of the drawing, in which position, the plates of all of the condenser units are out of operative relation and the same result may be accomplished by rotating the knob dial 22 in an opposite direction to the first named direction. On the other hand, if any one of the condenser units is retained in stationary position by the disengagement of the gear 19 of such unit from the gear 20, it will be necessary to rotate the adjacent unit or units through an arc of one hundred and eighty degrees to entirely move the same out of operative engagement with such stationary unit.

It will also be understood that by virtue of the adjustment employed, all of the units may be adjusted into a position similar to that diagrammatically shown in Fig. 3 of the drawing, in which figures the plates of the unit 9 are in a position similar to the position assumed by the plates of such unit in Fig. 1 of the drawing, while the plates of the unit 8 are arranged at an angle of forty-five degrees to the first named unit, the plates of the unit 7 at ninety degrees, and the plates of the unit 10 at one hundred and thirty five degrees to the unit 9, and with the plates in such adjusted position, they may be all simultaneously operated through a single control and operating knob dial 22, or one or more of said units may be held stationary in a given adjusted position. It will also be apparent that any desired adjustment and operation of the several units may operate to produce, in a single condenser device of a given number of plates in each unit employed, a widely varying and long range of tuning. It must be further understood that the number of plates employed in each unit may be arranged to suit the particular apparatus in connection with which the condenser device is to be employed, the number of plates shown in the accompanying drawing being merely for illustrative purposes.

In the use of the condenser device, it will be understood that the circuit wires may be coupled with the separate condenser units in any desired manner in the control of a single or multiplicity of circuits or tuning coils. For example, oppositely arranged condenser units 8 and 10 may be coupled with one wire of a circuit or coil and the other opposed condenser units 7 and 9 with the other wire of said circuit or coil.

From the foregoing, it will be apparent that the construction shown in Figs. 1 to 3 inclusive consists of a plurality of condenser units, the plates of all of which may be moved relatively to each other or one or

more of the units may be retained in stationary position to function as stator plates, and the plates of the other units moved relatively thereto. In Fig. 4 of the drawing, I have shown a modification, in which I have 70 shown positioned outwardly of the movable units 7, 8, 9 and 10, stator plate units 7^a, 8^a, 9^a and 10^a with which the respective movable plate units are adapted to cooperate. With this form of construction, the stator plate 75 units 7^a-10^a respectively may be placed in predetermined circuits or if desired, constitute a single circuit and the movable plate units 7 to 10 inclusive may operate in every respect the same as the operation thereof 80 hereinbefore described with relation to Figs. 1 to 3 inclusive.

It will be understood that I am not necessarily limited to the specific shape or form of the movable condenser units herein shown and described, nor am I necessarily limited to the specific means of their operation; and various other changes in and modifications of the construction herein shown and described, may be made within the scope of the 90 appended claims, without departing from the spirit of my invention or sacrificing its advantages.

Having fully described my invention, what I claim as new and desire to secure by Letters Patent, is:

1. A condenser of the class described including a plurality of movable condenser units, said units being arranged side by side and in oppositely arranged pairs, the plates of oppositely arranged pairs of units being in common alinement and in spaced relation and the plates of the units at the sides of each unit being in cooperative relation with such unit and positioned in the plane 100 between and in spaced relation with the plates of such unit.

2. A condenser of the class described including a plurality of movable condenser units, said units being arranged side by side and in oppositely arranged pairs, the plates of oppositely arranged pairs of units being in common alinement and in spaced relation and the plates of the units at the sides of each unit being in cooperative relation with such unit and positioned in the plane 105 between and in spaced relation with the plates of such unit, and means whereby all of said units may be simultaneously operated.

3. A condenser of the class described including a plurality of movable condenser units, said units being arranged side by side and in oppositely arranged pairs, the plates of oppositely arranged pairs of units being in common alinement and in spaced relation and the plates of the units at the sides of each unit being in cooperative relation with such unit and positioned in the plane 120 between and in spaced relation with the plates of such unit, means whereby all of 125

said units may be simultaneously operated, and means for independently adjusting and operating the separate units.

4. A condenser of the class described including a plurality of movable condenser units, said units being arranged side by side and in oppositely arranged pairs, the plates of oppositely arranged pairs of units being in common alinement and in spaced relation 10 and the plates of the units at the sides of each unit being in cooperative relation with such unit and positioned in the plane between and in spaced relation with the plates of such unit, means whereby all of said units 15 may be simultaneously operated, means for independently adjusting and operating the separate units, and said last named means permitting the separate units to be held stationary in the operation of each or all of the 20 other units.

5. A condenser of the class described including a plurality of movable condenser units, said units being arranged side by side and in oppositely arranged pairs, the plates 25 of oppositely arranged pairs of units being in common alinement and in spaced relation and the plates of the units at the sides of each unit being in cooperative relation with such unit and positioned in the plane between and in spaced relation with the plates 30 of such unit, means whereby all of said units may be simultaneously operated, means for independently adjusting and operating the separate units, said last named means permitting the separate units to be held stationary in the operation of each or all of the 35 other units, and stator plate units for each of the movable plate units.

6. A condenser of the class described including a frame consisting of two frame members mounted in spaced relation, a plurality of movable condenser units mounted in and between said frame members, the 40 plates of each condenser unit being adapted 45 to be moved into and out of cooperative relation with the plates of other units disposed at the opposite sides of such unit, the plates of the second named units being spaced intermediate the plates of the first named 50 unit, a control and operating means for each unit, and means cooperating with the last named means for actuating all of said units.

7. A condenser of the class described including a frame consisting of two frame members mounted in spaced relation, a plurality of movable condenser units mounted in and between said frame members, the plates of each condenser unit being adapted 55 to be moved into and out of cooperative relation with the plates of other units disposed at the opposite sides of such unit, the plates of the second named units being spaced intermediate the plates of the first named 60 unit, a control and operating means for 65

each unit, means cooperating with the last named means for actuating all of said units, and said first named means being movable into inoperative position with relation to said last named means.

8. A condenser of the class described including a frame consisting of two frame members mounted in spaced relation, a plurality of movable condenser units mounted in and between said frame members, the 70 plates of each condenser unit being adapted to be moved into and out of cooperative relation with the plates of another unit or units disposed at the opposite side or sides of such unit, the plates of the second named 75 unit or units being spaced intermediate the plates of the first named unit, a control and operating means for each unit, means cooperating with the last named means for actuating all of said units, said first named 80 means being movable into inoperative position with relation to said last named means, and stator plate units adjacent the movable plate units and in connection with which said movable plate units are adapted to operate.

9. In a variable condenser, a plurality of movable condenser units arranged side by side and in opposite relation, and the plates of each unit being adapted to cooperate with 90 segment portions of the plates of units at opposite sides thereof in the operation of the condenser.

10. In a variable condenser, a plurality of movable condenser units arranged side by 100 side and in opposite relation, the plates of each unit being adapted to cooperate with segment portions of the plates of units at opposite sides thereof in the operation of the condenser, and stator plate units adjacent 105 each of the movable plate units and in connection with which the plates of the movable units operate.

11. A condenser of the class described including a plurality of movable condenser 110 units, two of said units being in inoperative relation with each other and another unit interposed between the first-named units, and the plates thereof being intermediate the plates of the first-named units and cooperating 115 therewith.

12. A condenser of the class described including a plurality of movable condenser units, two of said units being in inoperative 120 relation with each other and another unit interposed between the first-named units, the plates thereof being intermediate the plates of the first-named units and cooperating therewith, and means for operating each of said units.

13. A condenser of the class described including a plurality of movable condenser units, two of said units being in inoperative 125 relation with each other and another unit interposed between the first-named units, the 130

plates thereof being intermediate the plates of the first-named units and cooperating therewith, and means for simultaneously operating all of said units.

- 5 14. A condenser of the class described including a plurality of movable condenser units, two of said units being in inoperative relation with each other and another unit interposed between the first-named units, the 10 plates thereof being intermediate the plates of the first-named units and cooperating therewith, means for simultaneously operating all of said units, and means for adjusting each unit with relation to the other unit.
15. A condenser of the class described including a plurality of movable condenser

units, two of said units being in inoperative relation with each other and another unit interposed between the first-named units, and the plates thereof being intermediate the 20 plates of the first-named units and cooperating therewith, means for simultaneously operating all of said units, and means for adjusting each unit with relation to the other unit, said last named means also permitting the separate units to be retained against movement in the operation of the other unit or units.

In testimony that I claim the foregoing as my invention I have signed my name this 30

11th day of Feb., 1926.

GEORGE MERLE, Sr.
